A. HORCASITAS

HAIR CURLING APPARATUS

Filed Sept. 6, 1923

Inventor:
Andres Horcasitas
By George C. Heintz
Attorney.

UNITED STATES PATENT OFFICE.

ANDRES HORCASITAS, OF MEXICO, MEXICO.

HAIR-CURLING APPARATUS.

Application filed September 6, 1923. Serial No. 661,315.

To all whom it may concern:

Be it known that I, ANDRES HORCASITAS, a citizen of the Republic of Mexico, and a resident of Mexico city, Federal District, Mexico, have invented a certain new and useful Hair-Curling Apparatus, of which the following is a specification.

My invention relates to a hair curling apparatus which is simple of construction and 10 which may be electrically heated to an even and relatively low temperature.

It is an object of this invention to provide an apparatus of light weight so that several of them may be used at the same time without 15 inconvenience to the user and without having to be counterbalanced by weights.

It is another object of this invention to provide an apparatus the heat of which will not increase above a certain point so that the 20 hair may be left within the apparatus for an indefinite time without danger of being scorched or burnt.

In the accompanying drawings, Figure 1 is a side elevation of an apparatus made according to the invention. Figure 2 is a section taken longitudinally through the apparatus, and Figure 3 shows how the hair is wrapped around the hooked pin which enters the apparatus.

Like numerals indicate like parts in all the figures.

As shown in the drawings, the apparatus consists of an outer tube 1 and of an inner tube 2 of a smaller diameter, the upper extremity of this inner tube being flanged and turned over the inwardly curved upper extremity of the outer tube, so as to hold the same in place after the different parts of the apparatus have been assembled, besides 35 providing a smooth entrance for the hair to be introduced into the apparatus. Around the lower part of tube 2 there is a ring 3 in which rests a cap 4 which encloses the widened lower extremity of tube 1. A 40 wooden handle 5 is fastened to the lower end of tube 2 and closes it. An eye-screw 6 is screwed into this handle and through it passes the flexible cord 6^a for the electrical current.

In the space between tubes 1 and 2 is located the electrical heating element or resistance coil formed by a spirally wound wire 7 conveniently insulated between layers 8 and 9 of mica or other appropriate material.

The ends 10 and 11 of wire 7 pass through 55 a hole in the cap 4 and are connected with the twin cord 6^a which in turn may be connected with an electric current. The part of the cord passing through the eye screw 6 is preferably wound with wire 12 or otherwise 60 protected to prevent chafing of the cord.

A strand of hair 13 is wrapped, as shown in Figure 3, around the pin 14, after having first been passed under the hook 15 formed on one end of said pin, and secured at the 65 other extremity of the pin by a piece of string. Either before or after wrapping the hair around the pin, it is immersed into a suitable liquid, and the moist hair, wound around pin 14, is introduced into the inner 70 tube 2 as far as possible. As many strands of hair as are necessary to curl part or all of the hair are inserted into as many of these apparatus, and the electric current is turned on. The length and diameter of the 75 wire 7 forming the resistance coil is so calculated that only a temperature of about 195° F. is obtained in order to avoid scorching or burning of the hair. The vapors given off by the moist hair during its stay in 80 the apparatus escape through a hole 16 provided at the juncture of the tube 2 and the handle 5 and left open by a recess in said handle.

The hair is left in the apparatus for about 85 twenty minutes before being taken out, and the relatively low, even temperature produces lasting curls after the hair has been released from the pin.

What I claim is:

The combination with a handle, of a main supporting inner tube fixed on said handle and projecting in alignment therewith, said handle having an end on which said tube fits and provided with a recess the one side thereof whereby a pin may rest centrally on the inner end of the handle, said tube having a lateral opening communicating with said recess and being open at the end remote from the handle, and heating means on the exterior of said tube, comprising an outer tube mounted on the inner tube concentric therewith a pair of concentric insulating tubes mounted between the inner and outer tubes, and a resistance coil arranged between the 100 insulating tubes.

In testimony whereof I affix my signature.

ANDRES HORCASITAS.
